UNITED STATES PATENT OFFICE.

HANS M. BOE, OF MINNEAPOLIS, MINNESOTA, ASSIGNOR TO BOE MANUFACTURING COMPANY, OF MINNEAPOLIS, MINNESOTA, A CORPORATION OF MINNESOTA.

GREASE BUCKET PUMP.

Application filed February 9, 1922. Serial No. 535,379.

The object of my invention is to provide a pump adapted for insertion into a receptacle containing grease for dispensing or discharging a predetermined volume of the 5 greases when the plunger of the pump is operated. The receptacle may be a grease container or package, the pump being equipped with a suitable cover for closing the top of the container temporarily and being removable to allow the application of the pump to other containers.

A further object is to provide a pump device adapted for mounting in a tank or container, without being permanently attached thereto, so that it may be readily removed at any time for cleaning or other purposes.

A further object is to provide a pump device which may be utilized not only for 20 delivering a stated quantity of lubricant from the container or tank, but may also be used for withdrawing a lubricant from a crank case or for injecting a liquid, such as kerosene, into a crank case or gearing.

25 The invention consists generally in various constructions and combinations, all as hereinafter described and particularly pointed out in the claims.

In the accompanying drawings forming 30 part of this specification,

Figure 1 is a view, partially in section, showing the application of my improved pump to a can or grease container with the plunger in its depressed position,

35 Figure 2 is a vertical sectional view, showing the plunger in its raised position,

Figure 3 is a sectional view on the line 3-3 of Figure 2,

40 Figure 4 is a detail sectional view showing the position of the gate for controlling the admission of grease to the pump.

In the drawing, 2 represents the can or 45 grease container, usually made of sheet metal and having a suitable bail 3 for convenience in moving it from place to place.

The top of the container is open and has a bead 4 extending around the edge. 5 is a sheet metal cover, having a flange 6 fitting within the top of the container and forming 50 a tight joint with the walls thereof, the flange being sufficiently flexible to yield and accommodate itself to the inner surface of the container walls. The top of the cover has an annular flange 7 thereon that is seated on the bead at the top of the container

walls. A bar 8, preferably of metal, is fitted to the top of the cover and secured thereto by suitable means, such as a bolt 9, and said bar has depending heads 10 at the ends thereof on the underside of which cams 11 60 are provided to engage the under side of the bead 4, and secured to the heads 10 by suitable means, such as rivets 12. The cams have inclined surfaces to engage the bead 4 so that when the cams are rotated on their supporting rivets, the bearing of the surfaces on the bead will operate to draw the cover downwardly and seat it firmly on the top of the container.

A pump barrel 13 has its upper end 70 seated against the underside of the bar 8 and a plunger 14 has a rod 15 which projects through a hole in said bar and is provided at its upper end with a suitable handle 16 by means of which the plunger may be 75 raised and lowered in the barrel. The lower end of the barrel is mounted in a head 17. In this head is a chamber 18 which communicates with the open lower end of the barrel and with the interior of the container 80 through a port 19. A pipe 20 is connected with the chamber 18 and projects up through the bar 8 and is connected to a hose 21 having a suitable discharge nozzle 22. A valve 23 preferably of the gate type is arranged 85 to slide in guides in the head 17 to close or open the port 19 and a rod 24 projects up through the bar 8 in position to be grasped by the user of the device for operating the valve and opening or closing the passage 90 from the chamber 18 to the interior of the container.

A stop 30 is slidably arranged on the piston rod 15, and has a set screw adapted for setting the stop at any desired position on the rod, to limit downward movement of the plunger by engagement with the lid or closure 5. By this construction, accurately regulated quantities, or grease can be forced from the elongated delivery pipe, and a 100 quantity as small as three drams can be delivered. It will be noted that when the valve 23 is closed and the stop set in a predetermined manner, only that amount of liquid can be forced from the cylinder according 105 to the disposition of the stop 30.

By means of this gate valve, I can adapt the device for different purposes. When the gate is open, as shown in Figure 2, and the plunger raised to the position in said figure, 110

the pump barrel will be filled with the comparatively thick lubricant and then, upon closing the gate valve, a down stroke of the plunger will fill the pipe 20 and the hose 21 connected therewith to the nozzle at the end of the hose. Then the valve may be opened again and a fresh supply of the thick viscous lubricant drawn in from the container upon the upward movement of the plunger. This upward movement, however, will not disturb that body of the lubricant which has been forced into the pipe 20 and the hose 21 owing to its frictional contact with the walls of the pipe and hose and consequently a downward stroke of the plunger when the pipe and hose are filled will have the effect of immediately discharging a quantity of lubricant at the nozzle corresponding to the quantity drawn into the barrel on the up stroke of the plunger, a slight stroke of the plunger being immediately transmitted through the body of the lubricant to effect an instant discharge at the nozzle. When the device is in use, this presence of the lubricant in the pipe 20 and hose 21 will be a normal condition.

If the user wishes to remove lubricant from a gear case he can insert the nozzle of the hose into the case, close the gate valve in the pump and manipulate the plunger to suck the thick heavy lubricant backwardly in the pipe and hose and creating a suction at the nozzle and draw the heavy lubricant from the gear case into the hose, and if desired, he can draw kerosene or other liquid into the hose in the same way and then eject it into a gearing or any other desired point, which perhaps can not be conveniently reached with an ordinary means for discharging kerosene. I thus am not only able to draw the contents of the container into the pump and discharge it, as desired, but I may, by closing the passage between the pump and the container, utilize the pump as a means for drawing a lubricant, such as grease, or a liquid, such as kerosene, into the hose for discharge at some other point, the gate valve making a convenient and durable means for effectively cutting off the passage between the interior of the container and the pump.

It will be understood that this device is used for handling a thick heavy lubricant or a grease which, under normal conditions, will not flow but will move through the barrel and the discharge hose when the plunger is reciprocated. When the valve is open and the plunger is raised the grease will move through the intake port to the barrel and upon closing the valve, the grease on the down stroke will be forced outwardly into the discharge connection, comprising in this particular case the pipe 20 and the hose forming a continuation thereof. When the discharge connection has been filled with

grease to the nozzle and the valve opened, the up stroke of the plunger will draw the grease through the valve port instead of backwardly in the discharge connection as there is less resistance to the movement of the grease into the barrel through the valve port than there would be to its return through the holes and pipe 20 because of the frictional engagement of the grease with the walls of the pipe and the hose. Therefore, when the pipe and hose have been filled I may draw in a charge of grease from the container on the up stroke of the plunger and on the down stroke eject a corresponding volume from the nozzle. If the valve is closed and the plunger raised, the grease in the discharge connection will be drawn backwardly in the hose for a distance, creating a vacuum and a suction at the nozzle so that when the nozzle is inserted into a crankcase or other receptacle the lubricant therein will enter the nozzle and the discharge end of the hose and in that way may be collected and removed from the crankcase.

To use the apparatus, the pump is fitted into the top of the container, containing a quantity of grease, and when the pump plunger is raised to the upper end of the barrel, a vacuum created therein, it being understood, of course, that the plunger rod fits loosely in the bar 8 to allow the air above the plunger to escape, the barrel will fill with grease, as indicated in Figure 2, and then the operator will close the gate 23, shutting off communication between the chamber 18 and the interior of the container. The descent of the plunger will force the grease up through the pipe 20 to the hose and discharge nozzle. The gate can then be opened and the pump barrel will be filled when the plunger is raised to repeat the operation.

This device is extremely simple in operation, can be easily and quickly mounted on the container, and has no parts which are liable to become clogged or inoperative and delay or prevent the use and operation of the device.

Whenever desired, the apparatus may be easily and quickly detached from the container and removed for cleaning purposes or for attachment to another container or tank.

The pump apparatus can be easily adapted for any type of tank or container by a simple modification of the means for securing it on the top of said tank or container.

I claim as my invention:

1. A device of the class described, comprising a coupling, having three openings, a valve closing one of the openings at a point laterally of the other two, a pump cylinder delivering into one of the openings and secured to and communicating with the cou-

pling and having a piston, and a delivery conduit connected at one end with the other opening and secured to and communicating with the coupling the calibre of said delivery conduit being such as to substantially resist the flow of heavy fluid.

2. A device of the class described comprising a coupling providing a passage, a pump including a cylinder attached to the coupling and communicating at one end with the passage thereof, said coupling having a slot formed by sawing and traversing said passage, an element as a gate valve slidable in said slot, and having means cooperable with said coupling for guiding it, a delivery conduit as a continuation of the passage of the coupling, and of a calibre to substantially resist the flow of heavy fluid.

3. A device of the class described comprising a coupling providing a passage, a pump including a cylinder attached to the coupling and communicating at one end with the passage thereof, said coupling having a slot traversing said passage, an element as a gate valve slidable in said slot, and having means cooperable with said coupling for

guiding it, a delivery conduit as a continuation of the passage of the coupling and of a calibre to substantially resist the flow of heavy fluid, said delivery conduit lying at one side of the cylinder and said valve at the opposite side.

4. A device of the class described comprising a coupling providing a passage, a pump including a cylinder attached to the coupling and communicating at one end with the passage thereof, said coupling having a slot traversing said passage, an element as a gate valve slidable in said slot, and having means cooperable with said coupling for guiding it, a delivery conduit as a continuation of the passage of the coupling and of a calibre to substantially resist the flow of heavy fluid, said delivery conduit lying at one side of the cylinder and said valve at the opposite side, and said valve having means for operating it, which means is substantially parallel with the pump cylinder.

In witness whereof, I have hereunto set my hand this 1st day of February, 1922.

HANS M. BOE.
